Samuel H. Ransom, of Albany, N. Y.
Letters Patent No. 1214, dated Mar. 20, 1860.

The schedule referred to in these Letters Patent and making part of the same.

To all whom it may concern:

It is known that I, Samuel H. Ransom, of the City of Albany in the County of Albany, State of New York have invented or produced a new and original design for Plates for cast iron parlor stoves, and I do hereby declare that the following is a full and exact description of the same, reference being had to the accompanying drawings, and to letters of reference contiguous thereto.

"A" represents the Top of said Stove, with ornaments at proper intervals forming in combination with the other plate, the top of the Stove.

2

Des. 1214

"B" represents both the front and back of the stove with ornamental designs at proper intervals - which in combination with the other plates forms the front and back of the stove.

"C" represents both ends of the stove ornamented and which in combination with the other plates form both the ends of the stove.

"D" represents the Hearth plate or damper carved and ornamented to correspond with the other plates of the stove.

What I claim as my invention or production and desire to secure by letters patent, is the ornamental design and configuration of the top, sides, front and Hearth plate or damper, which in combination form a cast iron Parker Stove as described.
